UNITED STATES PATENT OFFICE.

EUGENE A. POLLARD, OF NEWPORT, NEW HAMPSHIRE.

TRACE-FASTENER.

SPECIFICATION forming part of Letters Patent No. 251,937, dated January 3, 1882.

Application filed July 1, 1881. (Model.)

To all whom it may concern:

Be it known that I, EUGENE A. POLLARD, of Newport, in the county of Sullivan and State of New Hampshire, have invented certain new and useful Improvements in Trace-Fasteners, 5 of which the following is a specification.

The principal object of my invention is to provide a cheap, simple, convenient, and durable device for connecting or attaching the traces 10 of a common light harness with the ends of the whiffletree in such manner as to permit of such traces being adjusted therewith at various lengths, either longer or shorter, as the case may require in different carriages on account 15 of the varying distances between the hold-backs, and trace-fasteners. Such differences heretofore have generally been provided for by adjusting the forward end of the trace by means of holes into which the buckle-tongue was inserted, as usually provided upon the sides of 20 the harness.

I am aware that to remedy these and other objections harness-traces heretofore have been especially constructed with projections or lateral ribs upon one side of such traces, near their rear end portions, adapted to be held and connected with the trace-fastener by means of a latch or cam-lever, the short end of which contacts with one of the projections formed 25 upon the trace; and as such construction and operation require that the traces be specially provided with such ribs or projections, it renders the same expensive and therefore objectionable.

I am also aware that trace-fasteners have heretofore been constructed of a loop having a spring-pivoted pin adapted to connect the trace by being passed through the common cockeye (formed or provided at the rear end 30 of the traces) and having a bearing upon the opposite side of the loop; but as said fastening would not serve such purposes as contemplated by my invention, as hereinafter more fully described and set forth, I need not further describe the same.

Figure 1 represents a longitudinal horizontal section through a trace-fastener constructed according to my invention. Fig. 2 represents a rear side elevation of the same.

50 A represents the ferrule portion by which the fastener may be secured to a whiffletree in

any suitable manner, the top and bottom portions of such ferrule being extended outward and curved forward, forming an open loop or frame, B B, having a front end, C, provided with a vertical opening or slot, D, and a right-angle bearing-plate, E, and between said upper and under sides of the loop or frame B B is pivoted the tongue H, having upon opposite sides or extending upward and downward therefrom vertical flanges or wing-like projections L L, which fill the space between the said top and bottom portions, B B, of the frame, as shown in Fig. 2. This flanged tongue-piece L L H is provided with a thumb-piece, F, by 60 which it may be turned rearward or upon its pivot N, when desired to release the trace P, by drawing the same backward until the short projection or tongue H is released from one of the holes T formed at intervals in the rear end 65 portion of the said trace P, when the same may be removed; or the trace may be adjusted so as to shorten or lengthen the same by inserting the projecting end or tongue H through the desired hole T. Then the projecting end of the 70 trace P is bent inwardly and passed between the lugs or beneath the loop R upon the rear side of the whiffletree-ferrule A, the lower edge of the trace P resting upon the bottom portion 75 B of the said fastener, as shown in Fig. 1, thus 80 retaining the end of the trace in such a position as to prevent its contact with the cross-bar of the carriage-shafts, and furthermore render the same neat in appearance, and protect it from contact with other foreign devices, as 85 would frequently occur were no such means employed to retain such end in this position.

When the trace and its fastener are in use it will be understood that the ends of the wings or flanges L L impinge against the inner face 90 of the trace P at their point of contact therewith when the short tongue H is received within one of the holes T provided in the trace, thus greatly diminishing the liability of such trace to break or tear off at the tongue-holes 95 T when subjected to an undue strain or load.

It will be seen that the short tongue H only projects beyond the ends of the flanges L the thickness of the trace or width of the slot D, and that the said tongue-body or flanges L L 100 contact with the end bearing-plate, C, whereby the same receives the whole strain without

the end of the tongue H projecting beyond such plate and resting against the right-angle plate E, thus allowing the tongue to be released from the trace by a slight back movement.

5 Having thus described my invention, what I claim is—

The trace-fastener consisting of the projecting curved open frame B B, having the plate E, and end C, provided with the vertical slot 10 or opening D, the pivoted tongue H, having

the flanges L L and thumb-piece F, said fastener being provided with the socket A, having the lugs or loop R, all being constructed and arranged for securing and adjusting the trace P, having the holes T, substantially as shown 15 and described.

EUGENE A. POLLARD.
